UNITED STATES PATENT OFFICE

HERBERT H. DOW AND GUY H. CANNON, OF MIDLAND, MICHIGAN, ASSIGNEES, BY
MESNE ASSIGNMENTS, TO THE AIR PREHEATER CORPORATION, OF NEW YORK,
N. Y., A CORPORATION OF NEW YORK

AIR PREHEATER

Application filed July 6, 1925. Serial No. 41,565.

One particular field of use for the present improved air preheater is as an apparatus for utilizing the hot flue gases from a furnace to heat the air required in the combustion of the fuel used in such furnace. It will be understood, however, that such apparatus may be employed in various other fields where it is desired to interchange heat between two fluid media.

The following may be enumerated as objects of the invention, viz:

To utilize the heat of stack gases in an apparatus that will not be rendered inoperative by the corrosive fumes contained in said gases.

To provide a simple and compact mechanism for the purpose stated and one that will not require any great amount of power for its operation.

To use any heat absorbing material, irrespective of whether it be uniform in size, shape or kind, or how it be arranged in chambers.

To obtain a long life for the preheater, because corrosion or disintegration of the heat absorbing material will not destroy the usefulness of the preheater. If the disintegrating particles collect and tend to obstruct the flow of the media through the packing, a cleaning will remove the small particles and the larger material may be used over again.

To obtain a high rate of heat transfer between the heat absorbing material and the media through turbulence and good scrubbing action caused by the irregular path that the media has to take while flowing through the heat absorbing material.

To obtain a continuous transfer of heat from the hot media to the heat absorbing material, simultaneously with heat being transferred from the heat radiating material to the cold media through the use of a plurality of chambers.

To have a minimum number of chambers necessarily out of communication with either the hot or cold media at any one time by the use of an odd plurality of chambers.

To shape the rotating valves so that end play in the driving shaft from expansion or wear in the step bearing will not affect the

clearance between the valves and the ports into the plurality of chambers, thereby preventing the contamination of the two media one with the other.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a central vertical section on the line 1—1 of Fig. 5 through an air preheating apparatus embodying the present improvements; Fig. 2 is a top plan view thereof; and Fig. 3 is a transverse section of the same, taken on the plane indicated by the line 3—3, Fig. 1; Fig. 4 is a perspective view of one of the valve cages, and Fig. 5 is a horizontal section therethrough.

The body of such illustrative apparatus comprises an odd plurality of circularly arranged chambers or compartments 1, formed by an outer cylindrical shell 2, an inner shell 3 concentric therewith, and the proper number of radial partitions. Such inner shell terminates short of the respective ends 4 and 5 of the outer shell and is connected with such ends by means of similar valve cages 6 and 7, which are open laterally to provide for the free inflow or outflow of gases, as the case may be, to or from the compartments or chambers 1. Such valve cages at the same time constitute a simple construction for insuring a good joint between the respective ports and the shells 2 and 3.

Where the apparatus is disposed with its axis vertical, as shown, a grid 8 is provided near the bottom of each compartment, approximately on the level of the lower end of the inner shell 3 where the latter is connected with the lower valve cage 7. This grid serves to support suitable heat absorbing packing material which substantially fills each compartment, this material, as shown, consisting of a plurality of short iron rings 9 placed end

upon end but in staggered relation so that the air or gas in traveling through the compartments necessarily has to follow a tortuous course. The radial partitions 10 whereby the 5 annular space between shells 2 and 3 is subdivided into such plurality of longitudinally extending compartments are best shown in Fig. 3, it being understood that the aforesaid filling material is packed between these partitions. 10

Mounted in the respective valve cages 6 and 7 are rotary valves 12 and 13, respectively, that are identical except that they project in opposite directions. Each valve, in other 15 words, consists of a plate-like base 12a and 13a, upon which the valve proper is mounted, the latter being in the form of a cylindrical wall rising from such base but of smaller diameter save on one side, where it projects 20 to the edge of the base and is provided with a port opening 12b, 13b. The valve includes radial plates 12c, which prevent admixture of the air and gas, in conjunction with the turned plates 12d, the upper edges of the 25 plates 12d merging with the annular plate section 12e which is equipped with a depending skirt 12f forming the upper boundary of the port opening 12b. The valves are fixed upon a common central shaft 15 that is journaled in suitable axially aligned bearings 16 within the shell 3. One end of said shaft, the 30 upper as shown, projects beyond the corresponding end of the apparatus and has secured thereto a beveled gear 17 whereby the 35 shaft with attached valves may be rotated at a predetermined rate.

The cylindrical body portion of the lower valve 13 has a close moving fit within a sleeve 20 which forms in effect one end of a duct 21 through which hot flue gas is supplied to the apparatus; while the body of the upper valve 12 similarly fits within a sleeve 22 that forms in effect one end of a duct 23 through which the flue gases escape to the stack or chimney after passing through the apparatus. The annular space between sleeve 20 and the valve cage 7 is connected with a chamber or duct 24 through which the air, after it has passed through the apparatus, is led to the furnace or other point where it is to be used; while similarly connected with the annular space between sleeve 22 and valve cage 6 is a duct 25 through which the cold air is led into the apparatus. Ventilating fans 26 and 27, mounted on a common power driven shaft 28, are located in such duct 25, through which the cold air is thus admitted, and in duct 23, through which the flue gases are discharged to the stack, respectively, so as to force the 60 flow of such air and gases to whatever extent may be necessary.

In operation, as the vertical shaft 15 rotates, the hot flue gases entering by way of duct 21 are caused to pass through port 13b in valve 13 into successive vertical compart-

ments 1 in the annular space between shells 2 and 3, whence they escape through port 12b of the upper valve 12 into the discharge duct 23. In thus passing through the chambers 1, these gases impart a considerable portion of their heat to the filling material 9 and this heat is then in turn taken up by the cold air entering the chambers 1 through duct 25 and the annular space between sleeve 22 and valve cage 6. After becoming thus heated, the air is discharged from the chambers 1 through the annular space between the sleeve 20 and valve cage 7 into duct 24. 70

The form of the valve bodies 12 and 13 is such that the compartment or compartments or chambers 1, through which the hot flue gas is being conducted, will be completely shut off against passage of the air therethrough and commingling of the latter with the flue gas accordingly prevented. It will also be understood that the length of chambers 1 may be varied to suit the requirements of the particular installation, the longer the path of travel of the hot gas and cold air, the more complete the heat interchange therebetween. 80

Other modes of applying the principle of our invention may be employed instead of the one explained, change being made as regards the mechanism herein disclosed, provided the means stated by any of the following claims or the equivalent of such stated means be employed. 90

We therefore particularly point out and distinctly claim as our invention:—

1. In a heat interchange apparatus, the combination of inner and outer concentric shells forming an annular chamber; radial partitions dividing said chamber into a plurality of circularly arranged compartments, the latter containing heat absorbent material adapted to permit a fluid medium to pass therethrough; a valve cage at each end of said inner shell adapted to communicate freely with said compartments; an inlet duct leading to and an exit duct from each of said valve cages; and a rotary valve in each of the latter adapted to place said compartments successively in communication with the inlet duct at one end and with the outlet duct at the other, and to place the remaining compartments similarly in communication with the other pair of ducts. 100

2. In a heat interchange apparatus, the combination of inner and outer concentric shells forming an annular chamber; radial partitions dividing said chamber into a plurality of circularly arranged compartments, the latter containing heat absorbent material adapted to permit a fluid medium to pass therethrough; a valve cage at each end of said inner shell adapted to communicate freely with said compartments; an inlet duct leading to and an exit duct from each of said valve cages; a rotary valve in each of the latter adapted to place said compartments 110

120

125

130

- successively in communication with the inlet duct at one end and with the outlet duct at the other, and to place the remaining compartments similarly in communication with the other pair of ducts; and a shaft disposed centrally within said inner shell, whereon said valves are mounted for rotation in unison.
3. In a heat interchange apparatus, the combination of inner and outer concentric shells forming an annular chamber; radial partitions dividing said chamber into a plurality of circularly arranged compartments, the latter containing heat absorbent material adapted to permit a fluid medium to pass therethrough; a valve cage at each end of said inner shell adapted to communicate freely with said compartments; an inlet duct leading to and an exit duct from each of said valve cages; and a rotary valve in each of the latter adapted to place said compartments successively in communication with the inlet duct at one end and with the outlet duct at the other, and to place the remaining compartments similarly in communication with the other pair of ducts, each of said valves comprising a circular base closing the corresponding end of said inner shell and a cylindrical portion rising from such base and provided with a ported offset portion whereby communication between the interior of said valve and the compartments in said annular chamber is limited to a definite number of such compartments at any one time.
4. In a heat interchange apparatus, the combination of inner and outer concentric shells forming an annular chamber; radial partitions dividing said chamber into a plurality of circularly arranged compartments, the latter containing heat absorbent material adapted to permit a fluid medium to pass therethrough; a valve cage at each end of said inner shell adapted to communicate freely with said compartments; an inlet duct leading to and an exit duct from each of said valve cages, one such inlet duct and the corresponding exit duct being aligned transversely of the axis of said chamber; a shaft extending centrally of said ducts; ventilating fans mounted on said shaft in each of said ducts; a rotary valve in each of said valve cages adapted to place said compartments successively in communication with the inlet duct at one end and with the outlet duct at the other, and to place the remaining compartments similarly in communication with the other pair of ducts.
5. In a heat interchange apparatus, an annular chamber containing regenerative material having passages extending therethrough, a supply channel and a discharge channel for a fluid to be heated, a supply channel and a discharge channel for a fluid to be cooled, and valve mechanism for controlling flow of one fluid through selected passages and flow of the other fluid through other passages, and means for moving said valve mechanism.
6. In a heat exchange apparatus, an annular chamber containing regenerative material having passages extending therethrough, a supply channel and a discharge channel for a fluid to be heated, a supply channel and a discharge channel for a fluid to be cooled, and valve mechanism for controlling flow of one fluid through selected passages and flow of the other fluid through other passages, for rotating and valve mechanism.
7. In a heat exchange apparatus, an annular chamber containing compartments, each compartment having regenerative material having passages extending therethrough, a supply channel and a discharge channel for a fluid to be heated, a supply channel and a discharge channel for a fluid to be cooled, and valve mechanism for controlling flow of one fluid through selected compartments and flow of the other fluid through other compartments, and means for moving said valve mechanism.
8. In a heat exchange apparatus, an annular chamber containing compartments, each compartment having regenerative material having passages extending therethrough, a supply channel and a discharge channel for a fluid to be heated, a supply channel and a discharge channel for a fluid to be cooled, and valve mechanism for controlling flow of one fluid through selected compartments and flow of the other fluid through other compartments, and means for rotating said valve mechanism.
9. In a heat exchange apparatus, an annular chamber, compartments in said chamber containing regenerative material having passages therethrough, a supply channel and a discharge channel for a fluid to be heated, a supply channel and a discharge channel for a fluid to be cooled, and valve mechanism for controlling flow of one fluid through said compartments in succession, and flow of the second fluid through compartments other than those through which the first fluid is flowing, and means for moving said valve mechanism.
10. In a heat exchange apparatus, an annular chamber, compartments in said chamber containing regenerative material having passages therethrough, a supply channel and a discharge channel for a fluid to be heated, a supply channel and a discharge channel for a fluid to be cooled, and valve mechanism for controlling flow of one fluid through said compartments in succession, and flow of the second fluid through compartments other than those through which the first fluid is flowing, and means for rotating said valve mechanism.
11. In a heat exchange apparatus, an annular chamber, compartments in said chamber

containing regenerative material having passages therethrough, a supply channel and a discharge channel for a fluid to be heated, a supply channel and discharge channel for a fluid to be cooled, and valve mechanism for controlling flow of one fluid through said compartments in succession, and flow of the second fluid through compartments other than those through which the first fluid is flowing and in countercurrent direction, and means for moving said valve mechanism.

12. In a heat exchange apparatus, an annular chamber, compartments in said chamber containing regenerative material having passages therethrough, a supply channel and a discharge channel for a fluid to be heated, a supply channel and a discharge channel for a fluid to be cooled, and valve mechanism for controlling flow of one fluid through said compartments other than those through which the first fluid is flowing and in countercurrent direction, and means for rotating said valve mechanism.

CERTIFICATE OF CORRECTION.

Patent No. 1,880,196.

October 4, 1932.

HERBERT H. DOW, ET AL.

It is hereby certified that error appears in the printed specification of the above numbered patent requiring correction as follows: Page 3, line 78, claim 6, for "for rotating and" read and means for rotating said; and that the said Letters Patent should be read with this correction therein that the same may conform to the record of the case in the Patent Office.

Signed and sealed this 9th day of October, A. D. 1934.

Leslie Frazer

Acting Commissioner of Patents.
